John P. Nease

UNITED STATES PATENT OFFICE

CLARE K. LIGHT, OF OSWEGO, NEW YORK, ASSIGNOR, BY MESNE ASSIGNMENTS, TO
THE DIAMOND MATCH COMPANY, A CORPORATION OF MARYLAND

PROCESS OF MAKING MATCHES

Application filed July 30, 1930. Serial No. 471,631.

This invention relates to a process of making matches having splints of permeable combustible material; its principal object being to provide for the economical and efficient treatment of the match splints with material which is effective to limit the flame to a relatively small portion of the splint when a match is ignited, and also with material which is effective to prevent the glowing of the burnt or charred part of the splint when the flame is extinguished.

The invention is especially designed for use in connection with a match making machine wherein the splints are inserted endwise, row by row, in an endless carrier and thereby rigidly held in spaced parallel relation and transported through the match making path, including wax (as paraffin) and match composition applying mechanisms.

In carrying out the invention in the preferred way the match splints, projecting from and supported in spaced parallel relation by the carrier, are treated with a material which permits the burning of the splints when they are ignited yet prevents their glowing when the flame is extinguished. This anti-glow material preferably consists of an ammonium phosphate solution with which the splints are impregnated, or of powdered ammonium phosphate with which the exposed surfaces of the splints are dusted or coated. The free end portions of the impregnated splints or the coated splints are dipped to a suitable depth into molten wax, as paraffin, and they are then exposed to the atmosphere for a brief interval of time to allow the wax to set. This done, the splints are dipped to a suitable depth in a solution of material, such as ammonium phosphate, adapted to impregnate and render practically fire-proof the portions of the splints above the waxed or paraffined portions, and such material is then effectually driven back from the waxed to the unwaxed portions of the splints by means of a hot fluid blast, as steam or hot air, which is projected longitudinally of the splints against the free extremities of the waxed portions.

Thereafter such extremities are tipped

with any usual or approved ignitable composition or compositions to form the match heads, whereupon the matches are conveyed through a suitable drying space, whence they are discharged from the carrier and packed.

55

In the drawing, which is a diagram of parts of a match making machine designed to carry out my hereinbefore described process, 1 designates a portion of an endless carrier in which match splints, 2, are endwise inserted, row by row, and thereby rigidly held in spaced parallel relation. The type of machine illustrated embodies a cutter head 3 having instrumentalities whereby succeeding rows of splints are cut from a block of wood and forcibly inserted in perforations in the carrier.

60

4 designates a sprayer located adjacent the cutter head and adapted to project upon and longitudinally of the splints borne by the carrier a fine spray or mist of material effective to prevent the glowing of the splint material when a match has been ignited and the flame extinguished. This material is preferably a concentrated solution of phosphate ammonium, about 3.5 Baumé, which is quickly absorbed by the splints; but, if desired, the material may comprise pulverized phosphate of ammonium which in a dry state adheres to and forms a light dust or coating on the exposed surfaces of the splints.

70

5 designates a bath of molten paraffin, or the like, in which the lower ends of the depending splints, after they leave the sprayer, are immersed to a depth corresponding with the desired inflammable area of the splints. If desired a suitable heater may be interposed between the sprayer and the paraffin bath, in order to ensure the drying of the wet impregnated splints before they are dipped in the bath.

75

6 designates a bath of free-flowing fire-resistant material in which the splints are immersed a suitable depth, preferably above the upper line of the paraffin; the baths being sufficiently spaced to permit the paraffin to set before the material of the second bath is applied. The fire-resistant material is preferably a concentrated solution of phosphate

80

100

ammonium, about 21.5 Baumé, which is effective to impregnate the exposed unparaffined portion of each individual splint.

The bath 6 is preferably of the kind illustrated in the Pardon Patent No. 1,641,193, dated September 6, 1927, wherein the splints are rapidly immersed in the impregnating solution and then slowly removed therefrom to obviate any liability of the formation and retention of globules of liquid on the free extremities of the splints.

After leaving the bath 6 the splints are carried upward across the path of a blast of hot fluid, as steam or hot air, which is projected longitudinally of the splints toward the carrier by means of a nozzle 7 in a manner to drive the fire-resisting solution from the paraffined portions of the splints to and upon the unparaffined portions, and also positively to drive the solution from the free extremities of the splints. This step is an important feature of my invention, as the presence of the fire-resisting material on the paraffin impairs the burning quality of the latter, while the presence of the solution at the extremities of the splints additionally precludes the efficient drying of the match composition in a reasonable time after the composition has been applied to the splints.

8 designates a composition containing vat equipped with a transfer roll 9 by means of which match head composition is applied to the lower paraffined ends of the depending splints after the splints have been subjected to the action of the steam or air blast.

I claim—

1. A process of making matches comprising applying wax to a portion of a splint at one end of the latter, then applying a free-flowing fire-resisting material to such portion, then blowing the material from such portion to and upon the unwaxed part of the splint, and finally applying match composition to the free end of such waxed portion.

2. A process of making matches comprising applying wax to a portion of a splint at one end of the latter, then applying a free flowing fire-resisting solution to such portion, then forcibly projecting a fluid upon and lengthwise of the waxed and unwaxed portions of the splints in a manner to drive the solution from the waxed to the unwaxed portion of the splint, and finally applying match composition to the free end of the waxed portion.

3. In a process of making matches whereof the splints have waxed and unwaxed portions and whereof the waxed portions are coated with fire-resisting material, the step of blowing said material longitudinally of the splints from the waxed portions to and upon the unwaxed parts of the splints.

4. In a process of making matches whereof the splints have waxed and unwaxed portions and whereof the waxed portions are coated

with fire-resisting material, the step of projecting steam upon and lengthwise of the splints against the free ends of the waxed portions in a manner to drive the said material from the waxed to the unwaxed portions of the splints.

5. In a process of making matches whereof the splints have waxed and unwaxed portions and whereof the waxed portions are coated with fire-resisting material, the step of projecting hot air upon and lengthwise of the splints against the free ends of the waxed portions in a manner to drive the material from the waxed to the unwaxed portions of the splints.

6. A process of treating rows of spaced apart match splints which are each held at one end in and project from a suitable carrier, comprising treating the exposed surfaces of the respective splints with an anti-glowing material, treating the free end portions of the said splints with wax, dipping the splints in a fire-resistant solution, and directing a hot fluid blast longitudinally of the splints against the free extremity of the waxed portions in a manner to drive the solution from the waxed to the unwaxed portions of the splints, and applying match composition to the free ends of the said waxed portions.

Signed at Oswego, in the county of Oswego and State of New York, this 18 day of July A. D. 1930.
